DUPLICATING SALES PAD

Edward Z. Lewis, Evanston, Ill., assignor to General Manifold & Printing Co., a corporation of Pennsylvania

Application June 18, 1934, Serial No. 731,171

10 Claims. (Cl. 282—26)

This invention relates to improvements in duplicating sales books or sales pads.

The object of the invention is to provide a novel book of this character, in the use of which only a small amount of manipulation is required and such manipulation as is necessary may be performed quickly.

Where sales books are used with carbons arranged in the usual way, to duplicate the order 10 slips, it is necessary to place removable stop cards under each set of forms to prevent carrying the impression through onto the underlying sets of forms. Where the carbon sheets are pulled out from between one set of forms and shifted to 15 the next set of forms, considerable manipulation is required.

In my improved sales book each set of forms consists of an odd number of sheets with transfer means, such as carbon, coated on the reverse 20 side i. e. the side opposite the face, on all but the bottom sheet of the group. The even numbered sheets are assembled upside down, i. e. with the carbon side up, with the result that the carbon coated sides of sheets 1 and 2 are in 25 contact with each other, as are also the carbon coated sides of sheets 3 and 4, the last sheet, number 5, having no carbon coating on its under side. With this arrangement it is impossible to transfer the impression from the top sheets to 30 any of the sheets beneath.

When it is desired to use the set of forms, the second and fourth sheets are pulled out and turned over, with the result that the first four sheets are then face up, the carbon coatings being 35 on the under side thereof, and as a result, anything written on the top sheet is transferred by the carbon coatings and appears on the face of the remaining four sheets in the usual manner. However, where the book is made up of a 40 series of such groups of forms, with an odd number of sheets to a group, the order written on the sheets of the first group is not transferred through to any of the sheets of the groups beneath it for the reason, as stated above, that the 45 carbon coated backs of the sheets below all face each other, in pairs.

Fig. 1 is a plan view of a five sheet group or form book, selected for illustration, part of the sheets being torn away to expose the sheets beneath;

Fig. 2 is a similar view with four of the five sheets lifted and rolled back on themselves to show the coated and uncoated surfaces;

Fig. 3 is a view of the same pad after the even 55 numbered sheets have been torn out and turned over;

Fig. 4 is a perspective view of a complete book;

Fig. 5 is a perspective view of a modified form;

Fig. 6 is a plan view of a further modification;

Fig. 7 is an additional modification;

Fig. 8 is a perspective view of another modification;

Fig. 9 shows the same pad partly cut away;

Fig. 10 is a perspective view of a further modification; and

Fig. 11 is a side view of an additional modification.

Although the book illustrated is made up of units of five sheets each, it is evident that three sheets would be the minimum and any odd number of sheets in excess of five may be used as well, to constitute the effective portion of said book. Other sheets may of course be added for different purposes, if desired.

In Figs. 1 and 2 the sheets, in the form of a 15 pad, as assembled by the manufacturer, are numbered 1, 2, 3, 4, 5, from top to bottom, the under sides thereof being numbered 1', 2', 3', 4', 5'. Each of said sheets has the necessary lines ruled 20 on the face thereof, with such printed matter as may be desired. The four upper sheets, i. e. all the sheets except the bottom one, have a carbon coating on one side thereof (the side opposite the ruled or printed side) as shown. The fifth or bottom sheet has no carbon coating thereon. 25 Sheets 1, 3 and 5, i. e. the odd numbered sheets, are right side up or face up, and the even numbered sheets, 2 and 4 are upside down, all five sheets being bound together at the top, as for example by means of staples 6, and the even 30 numbered sheets, at least, being perforated or otherwise weakened at 7, so that they may be detached.

It will be seen that the sheets, arranged as 35 shown, are not ready for use, as anything written on the top sheet will not be transferred to the sheets beneath for the reason that the carbon coated surfaces of sheets 1 and 2 face each other and in like manner the carbon coated 40 surfaces of the sheets 3 and 4 face each other. In order to use the book, sheets 2 and 4, which are upside down, are torn out, turned over, and returned to their places in the pad right side up, i. e. face up, after which any order written on 45 the top sheet is reproduced on the four sheets beneath, making a total of five copies. Fig. 3 illustrates the arrangement after said sheets have been turned over, the carbon coating 1' overlying the face 2' of the printed form beneath it.

To facilitate tearing out sheets 2 and 4, which 50 are perforated at the top in such a way as to make them more readily detachable than the remaining three sheets, said remaining sheets may be notched, preferably at the bottom, as shown at 8, whereby the two even numbered 55 sheets may be readily grasped by the thumb and finger and torn out without grasping the odd numbered sheets.

It will also be understood that the group of 60 five sheets forms part of a book consisting of a

large number of such groups of five sheets, each the same as that shown in Figs. 1 and 2, and all bound together at the top, as shown in Fig. 4, to provide a form book of considerable thickness. 5 This particular book does not show the notches at the bottoms of the odd numbered sheets as the even numbered sheets may, of course, be torn out one at a time without this added convenience, although it will be understood that Fig. 4 illustrates a book of sheets which may be provided with such notches if desired.

Fig. 5 illustrates a sales pad or book, generally similar to Fig. 2 and Fig. 4, but instead of notching the odd numbered sheets, the even numbered 15 sheets which are to be turned over are made longer than the odd numbered sheets so that they protrude at the bottom whereby they may be readily grasped by the thumb and finger and torn out without tearing out the adjacent sheets. 20 In this perspective view shown, the second and fourth sheets have been torn out, turned over as a unit, and reinserted, thereby reversing the order of said sheets, i. e. the fourth sheet occupies the second position from the top and the second 25 sheet occupies the fourth position, as indicated by the reference characters on each of said sheets. It will also be noted that the carbon coating is on the under side of each sheet.

Fig. 6 shows a further modification in which 30 the transfer coating or carbon does not extend entirely across sheets 1, 3 and 4. After sheets 2 and 4 have been torn out and turned over ready for use, they appear as shown in this figure, with the fully carbon coated side 2' of sheet 2 overlying the lowermost or number 5 sheet, the four 35 uppermost sheets having carbon extending nearly, but not entirely across the back so that the prices and the like written in the price column on the top sheet are transferred to the bottom sheet 40 but are not transferred to the intermediate sheets, which are to be turned over to the shipping department, the teamsters or others not concerned with these confidential details. In the act of tearing out these second and fourth 45 sheets and reinserting them in the manner described, it is assumed that in turning over the two detached sheets at the same time their relative positions are reversed, the original second sheet becoming the fourth sheet and vice versa, 50 as shown in this figure. It will be understood, of course, that these two sheets may be torn out, turned over and reinserted one at a time, in which case this second sheet would be made with its carbon coating extending less than the entire 55 distance across it and the fourth sheet would have its carbon coating extending all the way across it or at least covering the marginal area, in addition to whatever part of the remaining area it covered, so that after said two sheets had 60 been reinserted, the four top sheets would each have a vertical uncoated strip on the under side thereof, the same as shown in Fig. 6 as drawn. In other words, no items would appear in the price columns except those written on the top sheet and transferred to the bottom sheet. The 65 sheets that have been torn out and turned over in this particular group, Fig. 6, are longer than the remaining sheets, although of course they may be the same length, or some of them may 70 be notched as in Figs. 1 and 2.

In Fig. 7, the even numbered sheets may be joined at the bottom as at 9 and formed from a single folded over sheet 10. By grasping this projecting fold, the two sheets torn out may be 75 turned over as a unit, reinserted in the pad and

the entries made as previously described. In this particular pad the bottom sheet may be made longer than the others so that the protruding bottom portion may have printed matter thereon indicating the formal disposition of the sheet, 5 as for example "Office copy", and an identifying number. Also, the projecting fold 9 may have instructions printed thereon such as "Detach and turn over", and the upper sheet may be printed "Original", as shown. In this case where the 10 sheets are prepared, folded and arranged before printing, said sheets may be printed either singly or in a strip of such forms and afterwards separated by cutting, and the identifying number printed by the same impression of the printing 15 press. The carbon coating on the even numbered sheets should not extend below the lower edge of the upper sheet, as shown in Fig. 7.

The coating on the second and fourth sheets is preferably of a different color than the coat- 20 ing on sheets 1 and 3, which further helps identify them.

In the form shown in Figs. 8 and 9, the top sheet 11 has carbon on the bottom side thereof, the next sheet 12 has carbon on the top side or 25 face thereof and is joined at the bottom to the sixth sheet, hereinafter referred to. The third sheet 13 has carbon on the bottom thereof, the fourth sheet 14 has carbon on the top thereof, the fifth sheet 15 has carbon on the bottom 30 thereof, the sixth sheet 16 has carbon on the top thereof, this sheet being joined to the bottom of sheet 12 to form a loop. The bottom sheet 17 has no carbon on either side. Sheets 13, 14 and 15 are received within the loop 16. 35

The lower edge of the top sheet and in fact of all the odd numbered or alternate sheets may be notched out at the bottom as at 18, to provide an area to be grasped by the thumb and finger in detaching the even numbered sheets, which in- 40 cludes the loop. The sheets in Fig. 9 are cut away to make the arrangement clearer. The sheets, after being detached, are turned over and reinserted between any of the sheets in a manner which will be readily understood. 45

In Fig. 10, the top sheet 19 has carbon of a certain color on its under side, for example blue. The next sheet 20 has carbon of any color on one of its surfaces, for example black. This sheet has been detached and turned over so that 50 its coated side is down, as shown. The third sheet 21 has carbon on the back of a color different from that on sheet 20. The color used on sheet 21 may be the same as that on sheet 19 although this is not necessary as it may be any color as 55 long as it is different from the color of the sheet immediately above it. The bottom sheet 22 has no coating on either side.

As in other cases, each of these sheets may be sent to a certain department and all of the forms 60 for any department are in the same position in the pad. If the carbon on the back of one sheet is of one color, i. e. blue and the impression made on the opposite side of the same sheet is in another color, i. e. black, the legibility of a stack of 65 these sheets will not be destroyed by check marks made while they are being checked over in a pile. For example, in the case of a sheet with writing on the face in black and a blue color on the back, any check mark made with a pencil on one of the 70 upper sheets will be transferred to a number of successive lower sheets in blue, which blue color can readily be distinguished from the black and will indicate that these check marks are not part of the original entry. Also, the written material 75

cannot be obliterated by the rubbing together of adjacent superimposed sheets. This variation in color is particularly advantageous in cases where a teamster, for example, has one of the sheets handed to him and crumples it up and inserts it in his pocket with the result that the color from the back of the sheet is rubbed off on the front and would obliterate the writing more or less unless the color of the writing was different from the color of the carbon on the back.

Fig. 11 shows a series of seven superimposed sheets 23 to 29 inclusive, the even numbered sheets 24, 26 and 28 projecting beyond the odd numbered sheets and all of said sheets being bound together at one end at 30. This figure shows a side view of substantially the same pad shown in perspective in Fig. 5, except that the even numbered sheets have not yet been detached, and a larger number of sheets are used in making up the pad. The shorter sheets are arranged face up and the long sheets are arranged upside down, i. e. with the carbon on the top thereof until they are pulled out by the projecting edges and turned over, as will be clearly understood from the foregoing description.

Although I have referred to carbon coating, the invention is not limited to transfer means in the form of a coating applied directly to the back of the paper as the transfer means may be in the form of a separate sheet of carbon paper. These separate sheets are so positioned with reference to the sheets immediately above them that when certain sheets are torn out the carbon paper is torn out with them and when they are turned over the carbon paper is turned over with them. In the cases of sheets not torn out the corresponding carbon sheets remain in the pad with those sheets. With this arrangement each sheet in the pad has an underlying sheet of carbon paper arranged exactly the same and notched or otherwise, or perforated as if it were carbon coated instead of being provided with a separate sheet of carbon paper.

I claim:

1. A sales pad consisting of an odd number of superimposed slips, separably confined near one edge, all except the last one of which has transfer means on its reverse side, the odd numbered slips being arranged face up and the even numbered slips being arranged face down and having portions extending beyond the margins of the odd numbered slips above the same, whereby said portions may be readily grasped and removed from said pad.

2. A sales pad consisting of an odd number of superimposed slips fastened together at the top, all except the last one of which has transfer means on its reverse side, the odd numbered slips being arranged face up and the even numbered slips being separable from said pad, arranged face down, and projecting beyond the lower edges of the remaining slips, said projecting portions having no transfer means thereon.

3. A sales pad consisting of five slips bound together at the top, the first four slips each having carbon on the back, the first and third slips being arranged face up, the second and fourth slips being separable from said pad, arranged face down, and projecting beyond the lower edges of said first and third slips and having said projecting portions joined, whereby said joined portions may be grasped and detached from said pad, turned over and reinserted.

4. A sales pad consisting of an odd number of superimposed slips, all except the last one of which has transfer means on its reverse side, the odd numbered slips being arranged face up and the even numbered slips being separable from said pad, arranged face down, and having portions extending beyond the margins of the odd numbered slips above the same, whereby said portions may be readily grasped and removed from said pad, the extended slip nearest the top having its extending margin joined to the extending margin of the slip nearest the bottom.

5. A sales pad consisting of an odd number of superimposed slips, all except the last one of which has transfer means on its reverse side, the odd numbered slips being arranged face up and the even numbered slips being separable from said pad and arranged face down, one edge of the original and of the alternate or odd slips being cut out sufficiently to permit said even numbered slips to be grasped and detached.

6. A sales pad consisting of an odd number of superimposed slips, all except the last one of which has transfer means on its reverse side, the odd numbered slips being arranged face up and the even numbered slips being separable from said pad and arranged face down, the lower edge of the original and of the alternate or odd slips being cut out sufficiently to permit said even numbered slips to be grasped and detached, two of said even numbered slips being joined at the bottom.

7. A sales pad consisting of an odd number of superimposed slips, all except the last one of which has transfer means on its reverse side, the odd numbered slips being arranged face up and the even numbered slips being separable from said pad and arranged face down, the lower edge of the original and of the alternate or odd slips being cut out sufficiently to permit said even numbered slips to be grasped and detached, the upper and the lower even numbered slips being formed as a single slip looped about a plurality of the other slips.

8. A sales pad comprising three or more superimposed sheets separably secured at one edge, two of the adjacent sheets having transfer means on the reverse sides, said reverse sides facing each other, whereby an impression to be made on the upper of said two sheets may be transferred through the sheet beneath it only after detaching and turning over the latter to bring its normally upper side in contact with another sheet on which the impression is desired.

9. A sales pad consisting of an odd number of superimposed slips separably confined near one edge, each of said slips above the bottom one having transfer means on its reverse side, the odd numbered slips being arranged face up and the even numbered slips being arranged face down.

10. A sales pad comprising three or more superimposed printed forms separably secured at one edge, the two upper forms having transfer means on the reverse sides, said reverse sides facing each other, whereby an impression to be made on the upper of said two forms may be transferred to the form beneath it in properly spaced relation to the printed matter after detaching and turning over the lower of said two forms to bring its normally upper side in contact with the form below it and in registration therewith.

EDWARD Z. LEWIS.
